DESIGN FOR A VEHICLE TANK BODY

Edward H. Gill, Kansas City, Mo., assignor to
Andrew A. Kramer, Kansas City, Mo.

Application May 1, 1937, Serial No. 69,100

Term of patent 14 years

To all whom it may concern:

Be it known that I, Edward H. Gill, a citizen of the United States, residing at Kansas City, in the county of Jackson and State of Missouri, have invented a new, original, and ornamental Design for a Vehicle Tank Body, of which the following is a specification, reference being had to the accompanying drawing, forming a part thereof.

In the drawing:

Fig. 1 is a side elevation of my new design.

Fig. 2 is a top plan view thereof, and
Fig. 3 is a rear elevation thereof.

The new features of the design reside particularly in the portion thereof lying rearwardly of the vertical plane passing through the axial center of the rear wheel housing.

I claim:

The ornamental design for a vehicle tank body, substantially as shown and described.

EDWARD H. GILL.
